UNITED STATES PATENT OFFICE.

RALPH G. JACKSON, OF CHESTER, PENNSYLVANIA, ASSIGNOR TO CONGOLEUM COMPANY, INCORPORATED, OF NEW YORK, N. Y., A CORPORATION OF NEW YORK.

BLOCK PRINTING MACHINE.

1,409,862.

Specification of Letters Patent. Patented Mar. 14, 1922.

Application filed October 15, 1919. Serial No. 330,864.

To all whom it may concern:

Be it known that I, RALPH G. JACKSON, a citizen of the United States, and a resident of Chester, county of Delaware, State of Pennsylvania, have invented certain Improvements in Block Printing Machines, of which the following is a specification.

My invention relates to certain improvements in flat block printing machines, especially those adapted for printing rugs where border blocks and center blocks are used so as to print bordered rugs of different lengths.

One object of my invention is to design the machine so that traveling tripping blocks will actuate the mechanism for releasing the printing devices.

A further object of the invention is to arrange the carriers for the tripping blocks so that the blocks can be shifted in order to hold up certain printing blocks and to allow others to make impressions.

A still further object of the invention is to design the mechanism so that an operator at the feed end of the machine can so shift the tripping blocks that certain portions of the fabric can be passing through the machine without being printed upon.

Still another object of the invention is to reduce the waste, due to imperfections in the material, by adjusting the printing blocks so that a portion of the material can be cut out and a rug of a different size, from that for which the machine is set, can be printed.

Heretofore, if an imperfection occurred in the material the rug had to be printed and discarded, or the operator had to remove the material from the machine and cut out the several blocks by hand.

In the accompanying drawings:

Fig. 1 is a side elevation, partly in section, of sufficient of a flat block printing machine to illustrate my invention;

Fig. 2 is a sectional view on the line 2—2, Fig. 1;

Fig. 3 is a sectional plan view on the line 3—3, Fig. 1;

Fig. 4 is a diagrammatic side view of the entire machine;

Fig. 5 is a plan view of a portion of the feed end of the machine;

Fig. 6 is a view showing a rug printed by my improved machine; and

Fig. 7 is a diagram illustrating one feature of my invention.

1 is the frame of a flat block printing machine. 2 are the printing block carriers. 3 are the endless tapes passing around wheels 4, at each end of the machine, and operated by any suitable mechanism. The block carriers are raised by a cam 22 of the ordinary type. 5 is a table extending the full length of the machine between the tapes upon which the material to be printed travels. The tapes have pins 6 which engage the material *a* and feed it intermittently through the machine. The material is brought to the machine in a roll, as at *e*, Fig. 4, and passes through the machine, and, in the present instance, down an inclined plane 7 at the discharge end of the machine from which it is introduced into a drier of any suitable construction. At each block carrier is a latch 8, which engages the carrier and holds it up out of action. This latch is pivoted at 9 to the frame of the machine and is actuated by my improved mechanism, which will be described hereinafter.

Suitable mechanism is provided, which is not shown in the drawings, to supply the blocks with color. This mechanism can be any of the types now in common use.

Located at one side of the machine are brackets 10, which carry an endless band, or link belt, 11. 12 are guides forming three divisions 13^a, 13^b, and 13^c, for the tripping blocks 13, which are arranged in 18" units, in the present instance, as each printing block is 18" wide. The tripping blocks are made in three sections, which are pivotally connected so as to pass around the wheels at each end of the machine. In the present instance, there is a series of pivot rods 23 on which the block sections are mounted and these pivot rods are attached to the endless band 11 and when the blocks are shifted laterally the pivot rods guide them so that they will be held in proper alignment.

Each latch 8 has an arm 14 through which extends a vertical pin 19. A spring 21 is located in a pocket in the arm 14 of the latch 8 and bears against a projection 20 on the frame 1, Fig. 2. Projecting laterally from the pin 19 is a pin 15, which carries a roller 17. The outer end of the pin 15 is located in a slot in a rib 16 projecting from the bracket 10. The spring 21 tends to force the pin 19 down and holds the roller 17 in position to be actuated by the tripping blocks 13.

and at the same time holds the latch 8 in engagement with the printing block carrier 2, as shown clearly in Fig. 1.

The two intermediate guides 12 for the 5 tripping blocks are discontinued at the feed end of the machine, as clearly shown in Fig. 5, so as to leave a space for an operator to adjust the blocks so that they will travel in any one of the three guideways.

- 10 When a rug of a given length is to be printed on this machine, the tripping blocks are so located that certain blocks will travel in one guideway and others will travel in the other guideways. The rollers 17 on the 15 pins 15 can be adjusted so as to be brought in line with any of the three guideways. This arrangement enables rugs to be printed having borders and I find that three sets of blocks are necessary, one for the central sections α of the rug having a section of a border at each side of the end sections y and z , each having a continuation of the side borders and having an end border. Three different sets of blocks are necessary. 20 25 These blocks are duplicated, according to the number of colors in which the rug is to be printed.

If a rug, such as illustrated in Fig. 6, is to be printed, then for each impression of 30 the right and left border blocks there will be four impressions of the center blocks α . The tripping blocks are so arranged that they will release the printing blocks at the proper time to print portions of the fabric so that 35 each rug printed will be of a given length, say 108", if the printing blocks be 18" wide.

In the event of an imperfection, such as a tear, occurring in the fabric, the operator at the feed end of the machine will see the 40 tear as it comes from the roll e , and will so adjust the tripping blocks in the ways as to skip the imperfection and to print a rug border in advance of the imperfection, making a rug smaller than the standard size being 45 printed, and also printing a rug border on the fabric immediately after the imperfection is passed. The rug of this border may be of the standard length, or may be less, according to the character of the imperfection discarded. 50

While I have shown three divisions, or channels, for the tripping blocks, it will be understood that any number may be used without departing from the main feature of 55 the invention.

In the drawings, I have shown only one side of a block printing machine. I have shown the pivot rod 9 extending towards the opposite side of the machine, as in Figs. 2 60 and 3. There is a latch, similar to the latch 8, on the opposite side of the machine in order to hold the printing block carriers properly in the raised position.

If, for instance, there are four sets of 65 printing blocks, each having a different de-

sign, it will be necessary to have an additional division, or channel. When there are no imperfections in the fabric being printed, the tripping blocks remain in the position in which they were originally set. It is only 70 when there is an imperfection, or when it is desired to print a rug of a different size, that the tripping blocks are shifted.

I claim:

1. The combination in a block printing 75 machine, of a frame; a series of block carriers; means for actuating the block carriers; means for intermittently feeding material through the machine; a latch for holding each block carrier out of action; means 80 for extending longitudinally of the machine and traveling at the same rate of speed as the material; and tripping blocks carried by said means; said blocks being laterally adjustable.

2. The combination in a block printing machine, of a frame; reciprocating block carriers mounted on the frame; printing blocks mounted on the carriers; a latch for holding each block carrier out of action; means for intermittently feeding material to be printed through the machine; an endless carrier on one side of the machine; means for driving the carrier intermittently and at the same speed as the material being 95 printed; and a series of tripping blocks mounted on the carrier and arranged to be adjusted laterally in one of three positions, the latch having arms arranged to be actuated by certain blocks.

3. The combination in a block printing machine, of a frame; reciprocating block carriers spaced a given distance apart; means for operating the block carriers; means for intermittently feeding material 105 through the machine; a pivoted latch at each block carrier; springs for retaining the latches in engagement with the block carriers; a pin engaging the latch and having rollers adjustably mounted thereon; and an 110 endless carrier traveling at the same speed as the material being printed and having laterally adjustable tripping blocks thereon arranged to be shifted in alignment with certain rollers for actuating the latches.

4. The combination in a block printing machine, of a frame; a series of block carriers thereon; means for actuating the block carriers; means for intermittently feeding material through the machine; a latch for 120 holding each block carrier out of action, each latch having an arm; a spring bearing against said arm and tending to hold the latch in engagement with the block carrier; a vertical pin extending through the frame 125 and through the spring; a right-angled pin projecting from the said vertical pin and having a roller adjustable thereon; a series of divisions, or channels; a series of trip blocks arranged to travel in said channels; 130

and means for traversing said blocks at the same speed as the material to be printed.

5. The combination in a block printing machine, of a frame; reciprocating block carriers spaced a given distance apart; means for operating the block carriers; means for intermittently feeding material through the machine; latches for holding the block carriers out of action; an endless carrier at one side of the machine; means for

moving the carrier intermittently and at the same speed as the material being printed; a series of cross bars and tripping blocks pivotally mounted on the cross bars, said blocks being made in sections and capable of being moved laterally; and longitudinal guides for retaining the tripping blocks in a given position so as to actuate certain latches. 15

RALPH G. JACKSON.
